UNITED STATES PATENT OFFICE.

GEORGE L. KOLLOCK AND ROBERT P. MARTIN, OF SEATTLE, WASHINGTON, ASSIGNORS
TO ELECTRIC HAMMER COMPANY, OF SEATTLE, WASHINGTON, A CORPORATION
OF WASHINGTON.

ELECTRIC HAMMER.

Application filed March 22, 1922. Serial No. 545,819.

To all whom it may concern:

Be it known that we, GEORGE L. KOLLOCK, a citizen of the United States, residing at Seattle, in the county of King and State of Washington, and ROBERT P. MARTIN, a citizen of the United States, residing at Seattle, in the county of King and State of Washington, have invented certain new and useful Improvements in Electric Hammers, the following being a full, clear, and exact disclosure of the one form of our invention which we at present deem preferable.

For a detailed description of the present form of our invention, reference may be had to the following specification and to the accompanying drawing, wherein—

Fig. 1 is a longitudinal vertical section of an electric hammer containing our invention and

Fig. 2 is a horizontal section of the gearing and cam.

Our invention resides in the expedient of two oppositely rotating bevel-gears having reversely-set cams which, although rotating in opposite directions co-operate to periodically lift and release the hammer against the force of its operating spring.

In the drawing A represents the shell of an electric hammer which may be made in separable parts convenient for assembling and replacing of the several members, as is now well known in the art. B is the armature of the operating electric motor, and C the field magnet. The motor shaft extends axially of the machine and at its inner end is a bevel-pinion D which meshes with two parallel bevel gear-wheels E¹, E² and rotates them in opposite directions. Inside of each wheel is a two-step cam H, the one shown in Fig. 1 being in the gear-wheel E¹ and rotating in a clockwise direction. These cams act respectively in the projections, preferably rollers, rollers K¹, K² which project from the opposite sides of the ham-

mer F and twice in each rotation they co-operatively lift the hammer against the force of its operating spring G and release it. At each release the spring forces the hammer out and causes it to give a sudden impact or blow upon the tool which may be included in the chuck J at its extremity. It will be observed that the gear-wheels E¹ and E² have rearwardly projecting stub-shafts e¹ and e² which are journaled in bearings in the shell A. By this arrangement the space between the wheels is left free for the play of the inner end of hammer F and the rollers K¹, K² thereon.

What we claim as new and desire to secure by Letters Patent is:

1. An electric hammer, comprising an electric motor, a bevel-pinion on the motor shaft, two bevel gear-wheels both driven by the said pinion but in opposite directions, a hammer with projections on opposite sides thereof extended into the space between the gear-wheels, an operating spring for the hammer, and oppositely-rotating cams on the adjacent sides of the respective gear-wheels acting co-operatively on the said hammer projections.

2. An electric hammer, comprising an electric motor, a bevel-pinion on the motor shaft, two bevel gear-wheels facing each other with rear-side journals therefor and both engaging the said pinion, a hammer with opposite projections thereon extended into the space between the two gear-wheels, and oppositely-rotating cams on the inner sides of the respective gear-wheels acting co-operatively on the said hammer projections.

Signed at Seattle, county of King, State of Washington, this 10th day of March, 1922.

GEORGE L. KOLLOCK.
ROBERT P. MARTIN.
